PORTABLE BOOTH

Carl G. Thurnau, Utica, N. Y.

Application August 2, 1940, Serial No. 349,774

5 Claims. (Cl. 304—9)

My invention relates to a portable booth and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a portable booth within which work can be carried on without interfering with other operations. It will be found useful especially in factories to allow painters to paint or spray the walls, ceiling or other parts of the interior of the factory while the employees of the factory are engaged in other gainful operations.

Furthermore, the booth has a knock down frame that is adjustable which can be altered quickly and easily to allow for clearing obstructions or fixtures of the factory or other building in which the booth has been set up.

Moreover, the booth is provided with an air suction device, whereby the air within the booth including particles of dirt, dust or paint fumes or mist will be sucked therein and discharge only pure air to the outside of the booth preferably towards the ceiling of the building. The suction device has a screen or filter to collect the particles of dust, dirt or paint or paint fumes within the booth and thereby expel only pure air from said booth. The expelling of pure air from the booth will cause an inflow of air through the openings and over the top of the side walls of the booth, whereby to prevent any dirt, paint fumes or other foreign matter from collecting on any objects outside of the booth.

The floor of the booth is made adjustable for length or width to accommodate the same for different objects to be worked upon.

The booth is also equipped with a platform which catches any dropping of paint, dirt or tools that may fall from the hands of the painter.

The object of the invention will be understood by referring to the drawings in which,

Fig. 1 is a perspective view showing the portable booth installed about the rafters and supporting beams of a building and also showing it clearing other objects on the floor of said buildings.

Fig. 2 is a perspective view of the booth showing certain of the curtains partially drawn back for the purpose of disclosing the frame work.

Fig. 3 is an enlarged detail view showing a section of a suction fan and immediate parts employed.

Fig. 4 is an elevational view showing a central vertical section of the booth, parts being in full.

Fig. 5 is a detail enlarged view showing a perspective of the flooring and means for extending the same, parts being broken away.

Fig. 6 is a diagrammatic view of a wiring.

Fig. 7 shows an elevational end view.

Fig. 8 is a detail view showing a section of a T joint employed and immediate parts.

Fig. 9 is a detail view showing an elevational view of another sleeve member and immediate parts.

Referring more particularly to the drawings the device embodies a frame work which is held together by bolts, whereby it can be easily and quickly taken apart and again set up in any building or any location. The frame comprises four upright corner posts 1, 1, 1, 1 which serve both as standards for the frame and to aid in supporting the platform or flooring 2 in elevated position above the floor of the building. Side rails 3 are fastened by plates 4 to the upper portion of posts 1.

An auxiliary post 5 is bolted at 8 to each of the posts 1. A cross bar 7 is mounted on the upper ends of the pair of auxiliary posts 5, 5 and secured by bolts 8 to posts 1. A platform 10 consisting of narrow planks or boards 11 is supported on cross bars 7, 12 and attached by screw 9.

Intermediate of cross bars 7 is a cross bar 12 and another at the end attached by hanger plates 14 to side bars 15 which are in turn bolted at 16 to post 1.

Bracing bars 29, 20 used in pairs of each end of the frame are fastened to cross bar 7 at their upper ends by plates 21 and at their lower ends to post 1 and contiguous auxiliary posts 5 by a plate 22. Plate 22 projects down between said post 1 and the contiguous auxiliary post 5. A bolt 23 projects through all three to hold the same in place.

Bracing rails 24 are bolted to side rails 3 and side bars 15 to strengthen the same.

The means for extending platform 2 contemplates short auxiliary boards 25 that are slidably mounted on every other board 11 and adjacent the respective ends thereof. To this end each alternate board 11 has its opposite sides reduced at 31 to form a groove 32 between itself and the next board 11.

U shaped braces 35 partially surround board 11 and the auxiliary or extension board 25 mounted to slide thereon. Each of said U-shaped braces 35 is attached to auxiliary boards 25 by

screws 36. Each of said U-shaped braces 35 moves with said auxiliary board 25. A U-shaped guide member 40 is used, in each instance, to aid in limiting the sliding motion of each auxiliary board 25 axially along its corresponding board 11. Furthermore, each of the U-shaped guide members 40 is held to the contiguous board 11 by screws 41, whereby it does not move with said auxiliary board 25.

The means for enclosing the booth embodies curtains 50 supported above the platform 2. Moreover the means for supporting the curtains 50 contemplates a plurality of sleeve members 51 that are attached at convenient locations to side rails 3 by means of U-shaped hooks 52. The free ends of hooks 52 are bent at right angles at 53, whereby to engage in a removable manner the far side of side rails 3, whereas the middle portions of each of the said hooks 52 is welded or otherwise fastened to sleeve 51.

A vertically adjustable rod 55 is slidably mounted in each of the sleeves 51. It is held in vertical adjusted position by a winged set bolt 56 that is mounted in a threaded aperture in sleeve 51. The inner end of bolt 56 is adapted to engage rod 55. As a further means for holding rod 55 in adjusted vertical position, auxiliary sleeve 58 is slidably mounted on rod 55 above sleeve 51 and held at any given vertical position therealong by a winged set bolt 60 mounted in a threaded aperture in sleeve 58. The inner end of winged bolt 60 is adapted to engage rod 55. Auxiliary sleeve 58 will be found useful particularly when lowering rods 55 to limit the downward movement thereof.

Rings or eyes 61, 67 are formed on opposite sides of each of said sleeves 58. Hooks 68 attached to curtain rods 69 engage said eyes 61, whereby to hold the curtains 50 in folded back or gathered in position as illustrated in Fig. 2.

T joints 70 are attached in a rigid manner to the top of each of the adjustable rods 55. The upper portion 71 forms a sleeve for the sliding of adjustable tube 72 which is held in given position by a winged set bolt 73 mounted in a threaded aperture 74 formed in portion 71. The inner end of bolt 73 is adapted to engage tube 72, whereby to hold it in given position.

Removable short rods 75 are mounted at either end in contiguous adjustable tubes 72, 72, whereby to form a continuous support for the several curtains 50. The ends of tubes 72 are beveled at 76 to allow curtain holding rings 77 to slip easily thereover.

Each of the curtains 50 is provided with slide fasteners or other closing means 78, whereby they can be connected to each other to form a continuous wall if desired. Curtains 50 will allow for the clearing of steam pipes 80 or other obstructions in the building. Said curtains 50 can be drawn or gathered around the adjacent rod 55 by cords 69 having hooks 68 that engage eyes 61 on sleeves 58 as above mentioned. Said rings 77 will hold the curtains 50 to rods 75.

The means for supporting curtains 50, 50 on the end of the booth contemplates sleeves 51, 51 carrying vertical adjustable rods 55 having T shaped joints 70, as above described. Rods 82 are carried in the horizontal hollow parts 71 of T joints 70. To this end set bolts 73 are mounted in threaded apertures in parts 71, whereby the inner ends of said bolts 73 will engage said rods 82. The outer end of rods 82 support vertically disposed sleeves 86. Vertically adjustable rods 81

are carried in sleeves 86 and held therein by set bolts 88.

The upper free ends of rods 87 are provided with open recesses 89 for the resting of a removable horizontally disposed curtain rod 90.

Furthermore, each of the end curtains 50 has a split at 91 from the bottom upward located adjacent its end which can be closed by a slide fastener 78. The several curtains 50 will allow 10 for the projection of different obstructions or fixtures annexed to the factory building such as pipes 88. Moreover, curtains 50 will vary in width, if desired, whereby to adapt the curtains to the different obstructions of the building that 15 would otherwise interfere.

The means for creating a suction of air, whereby to collect the fumes, dust, dirt, paint or paint mist in the booth and expel only pure air to the exterior embodies a fan 93 mounted to rotate 20 with the power shaft 94 of an electric motor 95 connected by wires 96, 96 to socket 97 secured to some part of the frame at flooring 2. Socket 97 can be connected by an electric circuit to any 25 electric source of supply. Motor 95 is mounted in a hollow cylindrical casing 98 and is held in suspension therein by brackets 99, 99 attached at one end to casing 95 and at the other to the casing 100 of motor 95.

Cylindrical casing 98 projects down through a 30 suitable aperture in platform 2. Angle iron brackets 101 are welded to casing 98 at one end and at the other are fastened by screws 102 to the boards 11 of platform 2.

The lower end of cylindrical casing 98 projects 35 down into a rectangular air conduit 103. Conduit 103 has its upper lateral edges bent at right angles into horizontal position to form flanges 104, 104 which rest against the lower surface of platform 2. It is held in given relation to plat-

40 form 2 by a metal strap 105 secured at one end to one of the cross bars 7 and at the other to intermediate bar 12. A screen 106 is disposed on the top of conduit 103, whereby to collect the fumes, dust, dirt, paint or paint mists. It is held 45 by wire 108.

Conduit 103 is made in sections that are telescoped together to conform to the width of platform 2. Elbows 107, 107 have a sliding fit with the respective ends of conduit 103, whereby to direct the outgoing pure air towards the ceiling of the room.

The suction fan 93 will reduce the air pressure 55 within the booth and thereby cause a flow of air through the openings and over the top of the walls of the booth which has no covering. This inward flow of air will not allow the escape of dirt, paint mist or other foreign matter from the booth, which would otherwise have a harmful result on the fixtures or other parts of the building or merchandise stored therein.

Brackets 111 are attached to the lower ends of each of the posts 1 and its contiguous auxiliary posts 5. Each of said brackets 111 carries a shaft 112 forming a bearing for rollers 113 mounted to 60 turn freely on said shaft 112.

The operation of the booth is effected by setting up the frame work within the building or other desirable location in which it is to be used in painting or spraying certain portions thereof. In setting up the frame work the cross bars 7, 7 are mounted on auxiliary posts 5, 5 and then bolted at 8 to posts 1.

The platform consisting of boards 11 and auxiliary or extension boards 25 is placed across

cross bars 7, 7, intermediate cross bar 12 and end cross bar 12.

Sleeve members 51 will be mounted on side rails 3 and the rods 55 adjusted as to the proper height to reach near the ceiling of the building or rafters 118. Curtains 50 of the proper width to avoid obstructions 80 of building will be hung on rods 75 by rings 77. The end curtain 50 is hung to rod 90 by said rings 77. The slide fasteners 78 will be used to close the several curtains 50 about the obstruction such as pipes 80 of the building.

Suction fan 93 will be started, whereby to draw all the fumes, dust, dirt, paint or paint mist into conduit 103 where they will collect on screen 106. The pure air only will be allowed to escape from the interior of the booth, whereby to prevent any of the paint or paint mist or other foreign substance from injuring other parts of the building, machinery or merchandise outside of the booth. There being no top to the booth the inrushing air to replace that which is expelled will aid also in preventing the aforesaid paint or paint mists or other foreign matter from reaching the exterior of the booth.

The framework can be pushed into place on its rollers 113 mounted to turn on shafts 112 carried in metal brackets 111 fastened to the lower end of each of the posts 1 and its contiguous auxiliary post 5.

A canvas sheet 119 will be spread on the floor of platform 2 to prevent any paint or foreign matter from escaping downward on the floor of the building. There will be an aperture 116 formed in the canvas sheet 115 to encircle the conduit 103.

Fig. 1 shows the portable booth in connection with the rafters 118 of the building and other parts including the window frame 120 and stationary seat 121 attached to the building. It also shows the booth moved over an obstacle such as container 122.

Having thus described my invention what I claim as new and desire to secure by Letters Patent is as follows:

1. In a portable booth, uprights for supporting a platform and side bars, sleeve members attached to said side bars, adjustable rods mounted in said sleeves, horizontally disposed rods carried by said last named rods, curtains carried on said horizontal bars, a hollow casing mounted in said booth and a fan mounted in said hollow casing to cause an outflow of air from the booth to said hollow casing, whereby it will prevent fumes and particles of dust from progressing outward from said booth.

2. In a portable booth, uprights having wheels attached thereto, a platform mounted on said uprights, extending members movably mounted on said platform, bars secured to said uprights, adjustable sleeves carried by said bars, rods mounted in said sleeves, other rods carried by said last named rods to support curtains and allow for obstructions thereto, an air conduit mounted in said booth and a fan mounted in said conduit to cause an outflow of air from the booth through the said conduit, whereby to prevent fumes and particles of dust from progressing outward from said booth.

3. In a portable booth, a frame, wheels mounted to said frame, a platform carried by said frame, side bars mounted in said frame above said platform, sleeves mounted to said side bars, rods carried by said sleeves, sleeves carried by said last named rods and other rods mounted in said last named sleeves for supporting curtains and to allow for obstructions thereto, an air conduit mounted in said conduit and a fan mounted in said conduit to cause an outflow of air from said booth through said conduit, whereby to prevent fumes and particles of dust from progressing outward from said booth.

4. In a portable booth, a frame, an extensible platform, carried by said frame sides formed on said platform, members mounted to said sides, adjustable rods mounted in said members, couplings carried by said rods, sleeves carried in said couplings, adjustable rods mounted in said last named sleeves, whereby to support curtains, openings in said curtains to allow for the projection of obstructions, zipper fasteners for closing said curtains and a conduit having a fan therein mounted in said booth to cause an outflow of air from the booth through the said conduit, whereby it will prevent fumes and particles of dust from progressing outward from said booth.

5. In a portable booth, a frame mounted on wheels, an elevated floor comprising boards, other boards mounted to slide on said first named boards for extending the length of said floor, sleeves mounted on said frame, rods mounted to slide in said sleeves, other rods mounted on said first named rods, curtains carried by said last named rods, whereby to form an enclosure for said conduit, a hollow cylindrical conduit mounted in said booth, a conduit mounted in said booth, a fan mounted in said conduit, whereby to collect dust, dirt, paint and paint mist carried in the air within said conduit.

CARL G. THURNAU.
